ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

MACHINE FOR USE IN LASTING BOOTS AND SHOES.

1,117,087.

Specification of Letters Patent. Patented Nov. 10, 1914.

Application filed October 12, 1912. Serial No. 725,477.

To all whom it may concern:

Be it known that I, ADAM H. PRENZEL, a citizen of the United States, residing at Halifax, in the county of Dauphin and State of Pennsylvania, have invented certain Improvements in Machines for Use in Lasting Boots and Shoes, of which the following description in connection with the accompanying drawings, is a specification, like reference characters on the drawings indicating like parts in the several figures.

This invention relates to machines which are especially adapted for use in connection with the lasting of boots and shoes and is herein shown and described in an embodiment designed particularly for use in lasting stitch-down shoes. Up to the present time substantially all machines intended for use in the lasting of stitch-down shoes have been designed to shape at one operation either the whole upper or the heel or the toe portion of the upper. Progressive lasting, in which the upper has been brought into and secured in its final lasted condition in a step-wise manner, has been almost unused. It will be apparent that in the lasting of stitch-down shoes there are numerous disadvantages which result from the employment of machines with which it is attempted to last either the whole or a substantial part of the shoe upper at a single operation. In the first place, if the means for conforming the upper to the shape of the last is efficient for this purpose, it must necessarily, in the case of the lasting of stitch-down shoes, interfere with properly securing the upper in lasted condition. The most common practice with machines of this type has been to secure the upper in lasted condition by cementing the outturned flange down upon the outsole. It will be obvious, however, that even with the best cement this mode of securing the upper in lasted condition must necessarily be unsatisfactory and must be totally impracticable when the upper has been stretched considerably to conform it to the last. Although the machines with which it has been attempted to last either the whole or a substantial part of the upper at a single operation have been unsatisfactory, the problem of the progressive lasting of stitch-down shoes has presented so many difficulties that very few attempts have been

made to solve it. One of the most obvious difficulties has been to draw the upper down over the side of the last in order to conform the upper to the last and then, without releasing the upper, to secure it firmly in lasted position and at the same time leave the lower marginal portion of the upper outturned upon the projecting margin of the sole to form the outturned flange to which the sole is to be secured. It will be apparent that any fastening which is to hold the upper securely in its lasted position must exert at least a considerable part of its holding power close to the edge of the last. Not only have the lasting machines which have been in commercial use for lasting shoes been totally unadapted for the lasting of stitch-down shoes, but the fastenings employed in such machines have been unsuited for properly securing the stitch-down upper in its lasted condition.

An object of the present invention is to provide a machine for use in the lasting of boots and shoes which will be especially adapted to effect the progressive lasting of stitch-down shoes and by the use of which the upper may be conformed to the last more closely than has heretofore been customary in the manufacture of this type of shoes.

Another object of the invention is to provide a machine that will not only bring about a proper conformation of the upper to the last but will insert a fastening of a type peculiarly suited for securing the upper in lasted position and which may furthermore remain as a permanent fastening to reinforce the attachment of the sole to the upper.

Important features of the invention are the novel relative movement of the last and the upper engaging means whereby the upper is drawn down over the rounded sides of the last and conformed closely to the last, the provision of means for effecting an initial lasting movement of the shoe engaging parts before the fastening inserting mechanism is actuated whereby the probable lasting effect may be observed before the upper is secured in lasted position, the provision of novel means for gripping the upper when it is desired to secure more than the usual drawing or stretching action upon the up-

per, and the novel means for presenting the work for the fastening inserting operation whereby the fastening is so located as to be most effective as a securing means for all 5 purposes.

Other features and objects of the invention will appear from the following description and claims when considered in connection with the accompanying drawings.

- 10 In the accompanying drawings,—Figure 1 is a side elevation of a machine embodying the invention, the base being broken away to permit showing the machine on a larger scale; Fig. 2 is a detail perspective of the 15 parts to which the present invention particularly relates, these parts being shown in operative position; Fig. 3 is a detail side elevation showing the manner of using the machine when the work does not require 20 much stretching; Fig. 4 is a perspective view of a preferred form of nozzle.

The mechanism for making and driving the staples may be of any well-known type, that herein shown being substantially the 25 same as that described in United States Letters Patent to W. H. Borden, No. 1,016,930, granted Feb. 13, 1912. This mechanism is mounted in a head 2 carried upon a standard 4 and comprises a staple driver 6 attached 30 to a driver bar 8 which is spring-operated, the driver operating spring acting upon an arm 10 fulcrumed at 12 upon a bracket 14 carried by the head 2. The staple forming mechanism and the wire feeding mechanism 35 are identical with those described in the Letters Patent above referred to except that the parts are fitted to operate upon much finer wire than is usually used in this type of machine.

- 40 The driver 6 operates in a staple guiding throat which extends into a nose or nozzle 16 which is of a peculiar shape and which constitutes one of the characteristic features of the present invention. As shown in each of 45 the figures, this nozzle is tapered to a comparatively thin end, that is, the edge which is to engage the upper of the shoe to be lasted is comparatively thin from front to back. The dimension which extends along 50 the shoe or along the edge of the last is preferably sufficient to give a good bearing surface and is also preferably sufficient to carry a throat for a staple of substantial width. Further reference to characteristic 55 features of the nozzle 16 will be made hereinafter.

When the machine is to be used with a last having sharply curved portions along its lower edge it is advantageous to concave 60 the nozzle 16 transversely upon the side adjacent to the last as shown in Fig. 4. Furthermore, as shown in the drawings, a longitudinal concavity upon this side serves to accommodate the curvature of the transverse 65 contour of the last.

In one aspect the lasting operation consists in causing the nozzle 16 to force the upper into the angle between the last and the projecting margin of the sole of a stitch-down shoe or into the angle between the 70 shoulder of a shouldered stitch-down sole and the projecting margin of said sole, these two operations being considered to be equivalents. In order to effect the relative movement of the nozzle and last or the nozzle and 75 the sole against which the upper is to be pressed, means is provided for supporting the sole, and in the construction shown this means has a movement toward and away from the nozzle 16. The sole support herein 80 shown comprises an anvil 18 which has in its normal positions an inclined surface 20 which is offset at 22 to provide a shoulder in the line of the movement of the anvil toward and away from the nozzle 16, this 85 shoulder serving to support the sole against the work-clamping pressure and also against the thrust of the staple driving operation. To provide for varying the inclination of the surface 20 the anvil 18 is pivoted at 24 upon 90 a head 26 carried by a rod or post 28 arranged to slide vertically in a horn 30. The horn 30 is itself carried by a horn post 31 arranged to slide in a vertical bore in a bracket 32 which has a stem 34 clamped in 95 a second bracket 36 integral with the standard 4.

The anvil 18 is normally held in its different positions of angular adjustment by means comprising an arm integral with the 100 anvil 18 to which is pivotally connected a rod 40 threaded at its lower end and arranged to slide freely through an opening in an arm 42 rigidly connected to two studs 44 and 46 which extend from the post 28 105 through a slot 48 in the horn 30, these studs serving to prevent the post 28 from turning in the bore in the horn 30. A stop nut 50 and a set nut 52 are threaded upon the rod 40, the stop nut 50 being held normally in 110 engagement with the upper face of the arm 42 by a spring 54 which surrounds the rod 40 below said arm and bears against a second stop nut 56. An adjusting nut 58 serves to lock the stop nut in its different positions 115 of adjustment. The adjusting nut 58 serves also as a stop which co-operates with an adjustable stop constituted by a screw 60 threaded through an arm 62 attached to the horn 30. The screw 60 is provided with 120 a knurled head 64 by which it may be turned, and is locked in its different positions of adjustment by a set nut 66.

The anvil 18 is preferably arranged so that it may be moved into operative relation 125 to the nozzle 16 both by hand and by power. The provision for moving the anvil into operative relation to the nozzle 16 by hand is for the purpose of determining approximately the point at which the staple shall 130

be inserted to secure the upper in lasted position and to determine whether or not the particular relative movement of the nozzle and anvil will secure the desired lasting effect. The illustrated means for effecting the manual movement of the anvil into operative relation to the nozzle 16 comprises a lever 68 fulcrumed at 70 between ears formed upon a support 72 bolted to the bracket 32, the lever 68 being provided with a rounded end 74 which is confined in a slot 76 in the rod 28, provision being made for movement of said lever to effect movement of the rod and for movement of the horn 30 relatively to the lever 68, when the lever is stationary, by forming a slot 78 in one side of said horn of sufficient dimensions to permit the desired relative movements. The movement of the lever 68 to effect the movement of the rod 28 can be effected either by hand through a handle 80 or by connections to a treadle 82, the said connections comprising a chain 84 hooked at one end to said treadle and at its other end to the outer arm of the lever 68.

The illustrated power operated means for bringing the anvil 20 and nozzle 16 into co-operative relation to each other and for holding the parts in work clamping relation while the staple is being driven comprises a lever 86 fulcrumed at 88 in the bracket 32, this lever having a rounded front end 90 which is confined in a slot in the horn post 31. The other end of the lever 86 is pivotally connected with the lower end of a rod 92 which is connected at its upper end to the outer end of a lever 94 fulcrumed at 96 upon the head 2. Between its ends the lever 94 is provided with a cam roll which enters a cam groove in the side of a cam disk 98. The rod 92 is arranged to slide in the rear end of the lever 86 to provide lost motion for transmitting yielding pressure to the work through the horn 30. The means for transmitting yielding pressure comprises a spring 100 confined between the collar 102 clamped upon the rod 92 and a washer 104 bearing against the upper side of the lever 86.

From the foregoing description it will be noted that the anvil 20 may be first moved into co-operative relation to the nozzle 16 by hand and then clamped in operative position by a movement of the horn 30 through the connections with the cam 98, or the anvil may be moved into operative position at the same time that the movement of the horn 30 is effected. The preferable practice, however, is to secure the proper adjustment of the work between the nozzle 16 and the anvil 18 and the greater part of the wiping and stretching relative movement of these parts before the movement of the horn 30 is effected.

It will be noted that that face of the nozzle

which performs the wiping action hereinafter described, that is, the face of the nozzle which is adjacent to the last, is smooth, so that it will not injure the upper, an essential characteristic of the construction of the nozzle being the location of this face close to that line of direction of the relative movement of the nozzle and the sole support which passes through the delivery end of the staple guide in said nozzle. By this construction and arrangement of the lasting tool of this machine, for the first time in the art of making stitch-down shoes it is possible to stretch the upper of a stitch-down shoe over the last, wipe it down the side of the last into the angle between the last and the sole margin, and, while the upper is thus held in lasted position, insert a fastening in said angle so that it will secure the upper tightly against the two sides of said angle exactly in its lasted position.

In the illustrated construction it will be seen that the wiping face of the nozzle lies well within an angle of 25° to the line of direction of the relative movement of the nozzle and the sole support, a deviation of less than 25°, in other words a deviation at not more than a sharply acute angle, being essential both for securing a proper stretching and wiping action upon the upper, in order to draw the upper tight over the last and to wipe it down the side of the last into the angle between the last and the sole margin, and also for locating the staple or other fastening where it will secure the upper firmly and exactly in lasted position. The best results are obtained when the inclination of the wiping face to the direction of the relative movement of the nozzle and the sole support approximates parallelism as closely as is consistent with proper strength in the wall of the nozzle, it being also essential to proper lasting that the nozzle be so constructed that the delivery end of the staple guide in the nozzle will deliver the staple as close to the wiping face as is consistent with strength in this wall of the nozzle.

From an inspection of Figs. 2 and 3 it will be noted that the shoe to be lasted, which has been assembled upon the last, is presented to the machine by first placing the sole of the shoe upon the inclined surface 20 of the anvil 18 with the parts in such position that when the anvil 18 is moved toward the nozzle 16 the nozzle 16 will enter the angle between the last and the projecting sole margin, first engaging the angle formed by turning out the lower margin of the upper and wiping the upper down over the side of the last and forcing the angle of the upper into the angle between the last and the sole margin. To insure a proper wiping action of the nozzle over the side of the last and particularly

to insure tucking of the upper under the overhanging edge of the rounded side of the last, as, for example, in the region of the shank, it is desirable that there be a tipping 5 of the anvil, after the manual presentation of the work and after the anvil and the nozzle have been brought into coöperative relation to each other, so that the inclination of the surface 20 shall be somewhat steeper, 10 thus permitting the nozzle to force the upper under the overhanging edge and permitting the staple to be driven so that its legs will project under the bottom edge of the last and be out of the way of the fastening 15 used to secure the upper to the sole in the final attaching operation. This tipping movement of the anvil is provided for by the construction hereinabove described and the operation of this construction to secure 20 this tipping movement is as follows: The stop nut 50 is so adjusted that the spring 54 will hold the anvil at the proper inclination when the parts are in the position shown in Fig. 1, or, at least, when the adjusting nut 25 58 has been moved out of engagement with the screw 60. The shoe being placed in position upon the anvil 18 the operator either grasps the handle 80 or depresses the treadle 82 and moves the anvil up until the nozzle 30 16 has engaged the angle of the upper and forced it substantially into the angle between the last and the projecting sole margin. During this movement there will be some tipping of the anvil due to the fact 35 that the sole supporting surface of the anvil is in front of the pivot 24. This tipping will obviously be against the pressure of the spring 54. When the machine is started to drive the staple the rod 92 will be depressed 40 and through its connections with the lever 86 will cause the horn 30 to be lifted until the lower end of the slot 48 engages the lower stud 46 upon the rod 28. If the stop 45 60 has been adjusted so that it engages the lower end of the adjusting nut 58 before the lower end of the slot 48 engages the stud 46 it will be obvious that the rod 40 will be pushed upwardly thus rocking the anvil 18 about its pivot 24 whereby the nozzle 16 will 50 be permitted to draw the upper around under the overhanging portion of the last and force it tightly into the angle between the last and the sole margin. The inclination of the sole to the direction of the staple 55 driving movement will also be varied by this rocking of the anvil and the staple will thus be driven more nearly transverse to the direction of the pull of the stretched upper and also so that its legs project under the 60 last and out of the way of the latter fastenings.

For small work, such as children's shoes and sandals, it has been found that sufficient lasting and stretching can be effected 65 by relative movement of the sole support

and the staple guiding nozzle. In lasting the larger sizes of shoes it is sometimes found desirable to effect more stretching and drawing of the upper over the last than can be effected by the frictional engagement 70 of the nozzle with the upper and the relative movement of the nozzle and the sole support into work clamping relation to each other. In order to obtain a better hold upon the upper when it is desired to effect a 75 greater stretching or pulling than can be effected by the means hereinabove described, an upper gripping jaw 106 is provided, this jaw being arranged to clamp the upper against the rear face of the nozzle 16. The 80 jaw 106 is carried upon a slide 108 arranged to slide through guide openings in the head 2, this slide being held normally in its rear-most position by a spring 110 bearing at one end against one side of an opening 112 in 85 the head 2 and at its other end against a collar 114 clamped upon the reduced portion of the slide 108. The jaw 106 is adjustably mounted in the slide 108, being pivoted at 116 and being held in different positions of 90 angular adjustment about the pivot 116 by an adjusting screw 118 having at its upper end a rounded knob 120 which is confined in a bore 122 in the jaw 106, an opening into 95 this bore through the side of the jaw 106 being provided by means of a slot 124. The screw 106 is threaded through a bracket 126 attached to the lower side of the slide 108 and is locked in its different positions of adjustment by a set nut 128.

To effect the movement of the jaw 106 into clamping relation to the nozzle 16 against the action of the spring 110, manually operated means is provided comprising a bell-crank lever 130 fulcrumed at 132 between ears on a bracket extending from the head 2, one arm of the bell crank being provided with a slotted end 134 which receives a stud or screw 136 upon the side of the slide 108 and the other arm being arranged 105 either to be operated by hand or to be operated by connections to a treadle. In the construction herein shown the other arm of the bell-crank lever 130 is connected by a chain 138 to the treadle 82 to which the 110 lever 68 is connected. In this construction the parts are so timed that the jaw 106 will move into clamping relation to the nozzle 16 before the anvil 18 is moved into operative relation to said nozzle. It will be noted that the jaw 106 is recessed at 140 so that the anvil 18 may come up behind the jaw as it moves into coöperative relation to the nozzle 16. This movement of the anvil 18 is also necessary to effect the stretching of the 115 upper held by the jaw 106 against the nozzle 16. It will be understood that although the construction herein shown provides convenient means for operating the anvil 18 and the jaw 106 it is not necessary that they 120 125 130

be operated in the particular manner shown since either may be connected to the power operated mechanism independently of the other, or both may be connected with the power operated mechanism to operate in the necessary time relation to each other.

The mode of operation of the various parts hereinabove described has been set forth to some extent in connection with the detailed description of these parts, but in order that the mode of operation of the machine as a whole may be more clearly understood, a brief recapitulation of the manner of working of the different mechanisms and of their interrelation will be made.

The parts being in the position shown in Fig. 1 of the drawings, a shoe to be lasted, which has already been assembled on a last, is so presented to the machine that the sole 20 of the shoe will rest upon the inclined surface 20 of the anvil 18 with the upper outturned over the projecting margin of the sole and with the side of the last where the lasting is to begin substantially in line with the front face of the nozzle 16. If the shoe is of a size and kind which does not require such stretching as would be effected by the use of the jaw 106 this jaw is disconnected from the treadle 82. If, however, it is desired to use the jaw 106 the outturned portion of the upper is placed between the jaw 106 and the rear face of the nozzle 16 and the treadle 82 is then depressed, causing the jaw 106 to clamp the upper against the nozzle 16 and causing the anvil 18 to move 35 the sole and last into operative relation to said nozzle. As the anvil 18 is moved up toward the nozzle 16 it will be noted that the nozzle 16 will engage the upper in the angle formed between the side of the upper and its outturned flange and will not only wipe the upper downward over the side of the last but will force this angle into the angle between the last and the projecting sole margin, or, what is the same thing, into the angle between the shoulder of a shod- 40 dered sole and the marginal portion of said sole. The flange of the upper being held by the jaw 16, considerable stretching or pulling will take place about the end of the nozzle 16 as the nozzle forces the angle of the upper into the said angle between the last and the sole margin. The operator then starts the machine by moving his knee or 45 the side of his leg against the knee lever 142 upon a rock-shaft 144 having a horizontal arm 146 connected to the rod 148 which carries at its upper end a clutch operating wedge 150. The arm 146 surrounds the rod 148 and operates to move the rod by 50 engagement with one or the other of two adjustable collars 152, 154, attached to said rod. As the machine is started and before the staple is driven, the horn 30 will be 55 raised through its connection with the cam groove in the cam disk 98 and will cause the

anvil to clamp the work against the nozzle 16 for the reception of the staple.

As already pointed out in the detailed description of these parts, the movement of the anvil 18 to bring the last and sole into coöperative relation to the nozzle 16 will cause some tipping of the anvil against the tension of the spring 54 by reason of the fact that the nozzle engages the anvil in front of the pivot 24. When the horn is raised to effect the final clamping of the work and the final adjustment of the anvil 18 and the nozzle 16, if the stop 60 has been set to secure a further tipping of the anvil before the horn reaches the upper limit of its movement, the stop 60 will engage the coöperating stop formed upon the adjusting member 58 and will push the rod 40 up to cause the anvil to tip toward a vertical position, thus permitting the nozzle 16 to wipe the upper of the sole further about the last and under any overhanging portions of the side of the last. This tipping of the anvil also serves to bring the staple more nearly normal to the direction of pull of the stretched upper and to cause the legs of the staple to be driven into the sole under the last and out of the way of succeeding fastenings which are to be used in attaching the sole.

Although the machine as herein shown and described is adapted to exert automatically a clamping and lasting pressure upon the work just before the staple is driven, it has been found in practice that on light work very satisfactory results may be obtained by adjusting the machine so that the only lasting and work clamping pressure exerted upon the work shall be that produced by the manually operated means for moving the anvil 18 and nozzle 16 into coöperative relation to each other. Not only has it been found that satisfactory lasting results may be obtained by the manual operation of these parts, but it has also been found that the pressure exerted in effecting the lasting operation is sufficient to support the work for the staple driving operation.

To secure the most satisfactory operation of the machine it has been found that the adjustment of the anvil 18 should be such that with the length of staple used there is no opportunity for the staple to project through the bottom of the sole when lasting the upper directly to the outsole and that the inclination of the anvil should also be such that the staple will be driven into the sole substantially transverse to the direction of pull of the stretched upper. Although the angle of inclination of the anvil will vary with the nature of the work, the length of the staple, the thickness of the sole, etc., it is usually such that the staple will be inclined to the face of the sole at an angle of 45° or less. Such an inclination of the

staple, besides increasing the holding power of the staple, serves to bring the legs of the staple under the bottom of the last and therefore out of the way of the needle of the 5 sewing machine which is used in securing the welt, upper and sole together after the shoe has been lasted. Moreover, it has been found that staples inclined as herein shown and described do not tend to work out of 10 the sole by the flexing of the sole as do staples which are driven more nearly normal to the face of the sole.

It will be noted that the process of making 15 stitch-down shoes, in the practice of which this machine is particularly useful, is in itself novel and that the shoe produced by this process is also novel. The novel process and the novel shoe are made the subject-matter of separate co-pending applications, Serial No. 725,476, filed October 12, 1912, and Serial No. 863,128, filed September 23, 1914, respectively.

Having now described my invention what 20 I claim as new and desire to secure by Letters Patent of the United States is:—

1. A machine for progressively lasting 25 stitch-down shoes, comprising a lasting tool having an upper engaging end and presenting to the side of the last a smooth upper wiping face, said tool having formed therein a fastening guiding slot which extends approximately to that edge of said end formed by the intersection of said face and said end and which has its greater cross 30 sectional dimension arranged substantially parallel to said edge, in combination with sole supporting means, said tool and said supporting means being arranged to effect the upper stretching and wiping operation 35 by a relative movement along a line passing through the delivery end of said guide and forming a sharply acute angle with said face.

2. A machine for progressively lasting 40 stitch-down shoes, comprising, in combination, a lasting tool presenting to the side of the last a smooth upper wiping face and having formed therein a staple guide which has its delivery end so arranged and in such 45 close proximity to said face that the head of the driven staple comes substantially into the plane of the wiping action of said face, and means for presenting a stitch-down shoe 50 to be lasted to said tool, said means operating to move said shoe along a line passing through the delivery end of said staple guide and forming a sharply acute angle with said upper wiping face.

3. A machine for progressively lasting 55 stitch-down shoes, comprising, in combination, a lasting tool having an upper engaging end of substantial width and presenting to the side of the last a smooth upper wiping face, said tool being provided with a 60 staple guide having its delivery end in the

upper engaging end of said tool and arranged to guide a staple so that its legs will cross the plane of the wiping action of said face and that the head of the driven staple will lie substantially in said plane, and 65 means for effecting a relative lasting movement of said tool and a shoe to be lasted along a line passing through the delivery end of said guide and forming a sharply acute angle with said face. 75

4. In a machine for progressively lasting 80 stitch-down shoes, the combination with a lasting tool having an upper engaging end, of sole engaging means, said tool and said means being relatively movable in such manner as to cause said tool to engage the upper of a stitch-down shoe to be lasted, to stretch the upper over the last and to wipe it down the side of the last into the angle between the last and the sole margin, said 85 tool having formed therein a staple guide extending to the upper engaging end and arranged to guide a staple substantially to the edge of said end which is adjacent to the last and to maintain said staple substantially parallel to said edge, and presenting to the last a smooth upper wiping face which forms a sharply acute angle with that line of direction of the relative movement which passes through the end of said staple 90 guide. 95

5. In a machine for progressively lasting 100 stitch-down shoes, the combination with a lasting tool having an upper engaging end, of sole engaging means, said tool and said means being relatively movable to cause said tool to engage the upper of a stitch-down shoe to be lasted, to stretch said upper over the last and to wipe it down the side of the last into the angle between the 105 last and the sole margin, said sole engaging means being inclined to said direction of movement, and said tool having formed therein a staple guide extending to its upper engaging end and arranged to guide a 110 staple substantially to that edge of said end which is adjacent to the last and to maintain said staple substantially parallel to said edge, and presenting to the last a smooth upper wiping face which forms a 115 sharply acute angle with that line of direction of said relative movement which passes through the end of said staple guide.

6. In a machine for progressively lasting 120 stitch-down shoes, a lasting tool having an upper engaging end and presenting to the side of the last a smooth upper wiping face and having formed therein a fastening guide, said guide being arranged to guide a 125 staple substantially to that edge of said end which is formed by the intersection of said face and said end and to maintain said staple substantially parallel to said edge, in combination with sole engaging means, said tool and said engaging means being rela- 130

tively movable in such a direction that the wiping action of said wiping face will be approximately parallel to said direction of relative movement.

5. 7. In a machine for progressively lasting stitch-down shoes, a lasting tool having an upper engaging end, presenting to the side of the last a smooth upper wiping face and having formed therein a staple guide arranged to deliver a staple substantially at that edge of said end which is formed by the intersection of said face and said end, with the body of the staple substantially parallel to said edge, and sole engaging means, said sole engaging means and said tool being relatively movable to cause said tool to stretch the upper over the last and to wipe it down the side of the last into the angle between the last and the sole margin, and 20 said upper wiping face being so positioned with respect to said upper engaging end that its relative wiping movement will be approximately parallel to said direction of relative movement of said tool and said engaging means.

8. A machine for progressively lasting stitch-down shoes, comprising a lasting tool having an upper engaging end and presenting to the side of the last a smooth upper wiping face, and having formed therein a staple guide which is arranged to guide a staple substantially to that edge of said end formed by the intersection of said face and said end, with the staple substantially parallel to said edge, in combination with sole engaging means, said tool and said sole engaging means being arranged for relative movement to stretch the upper over the last and to wipe it down the side of the last into the angle between the last and the sole margin and the wiping face of said tool being inclined to said direction of relative movement at an angle of less than 25°; whereby the wiping action of said face will be approximately parallel to said direction of relative movement.

9. In a machine for progressively lasting stitch-down shoes, a lasting tool having an upper engaging end and a smooth upper wiping face extending away from said end at an angle of less than 115° to the end, said tool having formed therein a staple guide extending to the upper engaging end and arranged to guide a staple substantially to the edge of said end which is adjacent to the last and to maintain said staple substantially parallel to said edge, in combination with a sole engaging means, said tool and said sole engaging means being relatively movable in such manner as to cause said upper wiping face to stretch the upper over the last and to wipe it down the side of the last into the angle between the last and the sole margin.

10. In a machine for progressively last-

ing stitch-down shoes, lasting means comprising a staple guiding nozzle having an upper engaging end and an upper wiping face, the staple guide in said nozzle extending to said end and approximately to the 70 edge of said end which is formed by the intersection of said face and said end and being inclined to said face at an angle of less than 25°, in combination with sole engaging means, said lasting means and said 75 sole engaging means being rotatively movable along the line of the staple guide to stretch the upper over the last and to wipe it down the side of the last into the angle between the last and the sole margin. 80

11. In a machine for progressively lasting stitch-down shoes, lasting means comprising a staple guiding nozzle having an upper engaging end and an upper wiping face, the staple guide in said nozzle extending to said end and approximately to the 85 edge of said end which is formed by the intersection of said face and said end, said wiping face and also the face of said nozzle remote from said wiping face being each 90 inclined to said guide at an angle of less than 25°, in combination with sole engaging means, said lasting means and said sole engaging means being relatively movable along the line of the staple guide to effect 95 the lasting operation.

12. In a machine for progressively lasting stitch-down shoes, a lasting tool having an upper engaging end and an upper wiping face and having formed therein a staple 100 guide which extends to said end and approximately to the edge of said end formed by the intersection of said face and said end, said guide and said face being inclined to each other at an angle of less than 25°, in 105 combination with sole engaging means, means for effecting a relative movement of said tool and said sole engaging means along the line of the staple guide into work clamping relation to each other, and means for 110 driving a staple through said staple guide while said parts are in work clamping relation.

13. A machine for progressively lasting 115 stitch-down shoes, comprising, in combination, staple inserting means comprising a staple guiding nozzle having upon one side a thin wall transversely concaved whereby it may enter the angle between the last and the sole margin of a stitch-down shoe to be lasted, and may hold the upper in said angle 120 close to the curved edge of the last to permit a staple to be driven through the upper into the sole in close proximity to said edge of the last. 125

14. A machine for progressively lasting stitch-down shoes, comprising, in combination, staple inserting means comprising a staple guiding nozzle longitudinally concaved upon one side and provided upon the 13.

same side with a thin wall whereby the end of said nozzle may enter the angle between the last and the sole margin of a stitch-down shoe to be lasted and may hold the upper in 5 said angle close to the edge of the last while the concavity in said nozzle accommodates the curvature of the transverse contour of the last.

15. A machine for progressively lasting 10 stitch-down shoes, comprising, in combination, staple inserting means comprising a staple guiding nozzle tapered to a comparatively thin edge lying in the plane of the staple guiding opening in said nozzle, and 15 means for presenting a stitch-down shoe to be lasted to said inserting means in such manner that the thin edge of said nozzle enters the angle between the upper and its flange and guides the staple through said 20 upper into the angle between the last and the projecting sole margin, the wall of said nozzle adjacent to the last being concave in the direction of its length to accommodate the curvature of the transverse contour of 25 the last.

16. A machine for progressively lasting 30 stitch-down shoes, having, in combination, means for engaging the upper and wiping it over a face of the last, and means for presenting the shoe to be lasted to said wiping means, said last-mentioned means being arranged to rock as the wiping movement is completing to permit the wiping action to be 35 continued over an edge or a rounded portion of the last.

17. A machine for progressively lasting 40 stitch-down shoes, having, in combination, staple inserting means comprising a staple guiding nozzle tapered to an edge substantially in the plane of the staple guiding opening in said nozzle, and means for presenting a stitch-down shoe to be lasted to said staple guiding means in such a manner that said guiding means wipes the upper 45 down the side of the last into the angle between the last and the projecting sole margin, said presenting means being arranged to rock as the wiping movement of said guiding means is completing whereby said 50 guiding means may wipe the upper over the bottom edge or under any overhanging portion of the last.

18. In a machine of the class described, 55 staple inserting means comprising a staple guiding nozzle having near its end a thin walled portion of substantial lateral extent tapered to an edge lying substantially in the plane of the staple guiding opening in said nozzle, means for presenting a shoe to 60 said inserting means in such manner that the upper is engaged and wiped over the side of the last by said nozzle, and means for rocking the last at such a point in the shoe presenting movement that said nozzle will

wipe the upper over the bottom edge of the 65 last.

19. In a lasting machine, means for engaging the upper and wiping it over a face of the last, and means for then rocking the last to permit the wiping action to be continued over an edge or a rounded portion 70 of the last.

20. In a machine for lasting stitch-down 75 shoes, means for engaging the upper in the angle between the upper and an out-turned sole attaching flange and wiping the upper down over the side of the last into engagement with the sole, means for then rocking the last to permit the wiping action to be continued over the bottom edge of the last, 80 and means for inserting a fastening through the upper into the sole to secure the upper in lasted position.

21. In a machine for lasting stitch-down 85 shoes, means for engaging the upper in the angle between the upper and an out-turned sole attaching flange, means for effecting a rectilinear, relative movement of the last and said upper, engaging means to stretch the upper, and means for rocking the last to 90 cause the upper to be wiped over the bottom edge of the last, and means for inserting a fastening through the upper into the sole to secure the upper in lasted position.

22. In a machine for lasting stitch-down 95 shoes, means for engaging the upper in the angle between the upper and an out-turned sole attaching flange and wiping the upper down over the side of the last into the angle between the last and the projecting sole 100 margin, means for then rocking the last to cause the upper to be tucked in under any overhanging portion of the last, and means for inserting a fastening through the upper into the sole in said angle between the last 105 and the sole margin.

23. In a machine for lasting stitch down 110 shoes, fastening inserting means comprising a fastening guiding nose or throat, means for presenting a shoe to said fastening inserting means in such manner that said nose or throat will draw the upper down over the side of the last into engagement with the edge of the sole, and means operating after the operation of said presenting means for 115 rocking the shoe about the nose or throat to change the direction of the upper drawing action of the nose or throat.

24. In a machine for lasting stitch down 120 shoes, fastening inserting means comprising a fastening guiding nozzle, means for presenting the shoe to said inserting means in such manner that the nozzle will engage the angle between the upper and its flange and force it into engagement with the sole in the 125 angle between the sole margin and the last, and means operating after said presenting means to rock the shoe about the nozzle to

cause the nozzle to force the angle of the upper tight against the edge of the last and under any overhanging portion thereof.

25. In a machine of the class described, 5 fastening inserting means comprising a fastening guiding nozzle shaped to enter the angle between the last and the projecting sole margin of a stitch-down shoe, an inclined sole support arranged to support a 10 sole with the said angle in the line of the fastening guiding opening in said nozzle, said sole support being pivoted to rock about an axis at one side of said line, and means for yieldingly maintaining said sole 15 support at a predetermined inclination to said line.

26. In a machine of the class described, fastening inserting means comprising a fastening guiding nozzle shaped to enter the 20 angle between the last and the projecting sole margin of a stitch-down shoe, an inclined sole support arranged to support a shoe with the said angle in the line of the fastening guiding opening in said nozzle, 25 said sole support being pivoted to rock about an axis at one side of said line, means for yieldingly maintaining said sole support at a predetermined inclination to said line, means for effecting a relative work clamping 30 movement of said sole support and said nozzle, and means for rocking said sole support about its pivot as the parts come into work clamping relation to each other.

27. In a machine for progressively lasting 35 stitch-down shoes, a lasting tool comprising a staple guiding nozzle having an upper engaging end and a smooth upper wiping face, and a sole support, said tool and said support being relatively movable to cause said 40 tool to stretch the upper over the last and to wipe it down the side of the last into the angle between the last and the sole margin, said sole support having an inclined sole supporting face, and means upon said sole 45 supporting face arranged to engage the bottom face of the sole for preventing the sole from slipping over said face during the lasting operation.

28. In a machine of the class described, 50 staple guiding means, an inclined sole support offset at a point in its inclined surface upon which the bottom face of the sole bears to provide a supporting ledge in a plane which will intersect the plane of the sole face, and means for moving said sole support into work clamping relation to said staple 55 guiding means.

29. In a machine of the class described, 60 fastening inserting means comprising a fastening guiding nozzle shaped to enter the angle between the last and the projecting sole margin of a stitch-down shoe, an inclined sole support having a portion of its inclined face upon which the bottom face of

the sole bears offset in a plane which will intersect the plane of the face of the sole, and means for moving said support toward and away from said nozzle in the line of the fastening guiding opening in said nozzle. 65

30. In a machine of the class described, 70 fastening inserting means comprising a fastening guiding nozzle shaped to enter the angle between the last and the projecting sole margin of a stitch-down shoe, an inclined sole support having a portion of its 75 face in the line of the fastening guiding opening in said nozzle offset in a plane which will intersect the plane of the face of the sole, and means for effecting a relative movement of said sole support and said nozzle 80 into work clamping relation to each other.

31. In a machine for progressively lasting 85 stitch-down shoes, a lasting tool comprising a staple guiding nozzle having an upper wiping face, and means upon the side of said nozzle remote from said face for preventing the upper from slipping over the end of the nozzle during the upper wiping operation. 90

32. In a machine for progressively lasting 95 stitch-down shoes, a lasting tool comprising a staple guiding nozzle having an upper wiping face, and toothed means upon the side of said nozzle remote from said face for preventing the upper from slipping over the end of the nozzle during the upper wiping operation. 95

33. In a machine of the class described, fastening inserting means comprising a fastening guiding nozzle shaped to enter the 100 angle between the last and the projecting sole margin of a stitch-down shoe to be lasted and to guide a fastening into said angle in position to confine said upper in the vertex of said angle tightly against both 105 sides of said angle, means for gripping the marginal portion of the upper of said shoe and holding it upon one side of said nozzle, and means for effecting a relative movement of the nozzle and the last while the upper is held by said gripping means to cause the upper to be drawn tight about the end of the nozzle and to be carried by said nozzle into the said angle between the last and the sole margin. 110

34. In a machine of the class described, fastening inserting means comprising a fastening guiding nozzle shaped to enter the angle between the last and the projecting sole margin of a stitch-down shoe, an inclined sole support adapted to support a shoe with the said angle presented in the line of the fastening guiding opening in said nozzle, means upon the side of the nozzle remote from the last for gripping the marginal portion of the upper, and means for effecting a relative movement of said parts to cause the upper to be pulled 120 125

tight over the side of the last and over the end of the nozzle as the nozzle enters the angle between the last and the sole margin.

35. A machine for progressively lasting 5 stitch-down shoes, comprising, in combination, fastening inserting means comprising a fastening guiding nozzle shaped to enter the angle between the last and the projecting sole margin of a stitch-down shoe to be 10 lasted, and means for clamping the marginal portion of the upper of said shoe against the side of said nozzle remote from the last.

36. A machine for progressively lasting 15 stitch-down shoes, comprising, in combination, fastening inserting means comprising a fastening guiding nozzle shaped to enter the angle between the last and the projecting sole margin of a stitch-down shoe to be 20 lasted and to guide the fastening into the sole in said angle, means for clamping the marginal portion of the upper of said shoe against the side of said nozzle remote from the last, and means for effecting a relative 25 upper stretching movement of said nozzle and said last after the upper is clamped.

37. In a machine of the class described, fastening inserting means comprising a fastening guiding nozzle tapered to an edge in a 30 plane which includes the fastening guiding opening in said nozzle, whereby said nozzle may enter the angle between the last and the projecting sole margin of a stitch-down shoe and guide a fastening into the sole in said 35 angle and means for clamping the marginal portion of the upper of said shoe against the side of said nozzle remote from the last, said means being shaped to provide for the accommodation of the sole margin when 40 the shoe is presented to the inserting means with the sole inclined to the direction of insertion of the fastening.

38. In a machine of the class described, fastening inserting means comprising a fastening guiding nozzle tapered to an edge 45 in a plane which includes the fastening guiding opening in said nozzle whereby said nozzle may enter the angle between the last and the projecting sole margin of a stitch-down 50 shoe and guide a fastening into the sole in said angle, means for clamping the marginal portion of the upper of said shoe against the side of said nozzle remote from the last, said means being shaped to provide for the accommodation of the sole margin when 55 the shoe is presented to the inserting means with the sole inclined to the direction of insertion of the fastening, and means for effecting a relative upper stretching movement of the 60 last and the nozzle after the upper has been clamped.

39. In a machine of the class described, fastening inserting means comprising a fas-

tening guiding nozzle shaped to enter the angle between the last and the projecting 65 sole margin of a stitch-down shoe, means for clamping the upper margin against the side of said nozzle remote from the last, means for effecting a relative upper stretching movement of the nozzle and the last in such 70 manner that the sole is presented to the inserting means at an inclination to the direction of insertion of the fastening, and means for rocking said last about the nozzle and the clamping means to cause the upper to be 75 tucked under any overhanging portion of the last.

40. In a machine of the class described, means for gripping the marginal portion of 80 the upper of a stitch-down shoe, and means for effecting a relative upper-stretching movement of the last and said gripping means to draw the upper down over the side of the last, said upper gripping means being shaped to carry the angle of the upper into 85 the angle between the last and the sole margin as the upper stretching movement is completing.

41. In a machine of the class described, means for gripping the marginal portion of 90 the upper of a stitch-down shoe, and means comprising an inclined sole support for effecting a relative movement of the last and the gripping means to cause the upper to be 95 drawn down over the side of the last, said gripping means being so shaped and said sole support being so positioned with respect to said gripping means that the gripping means carries the angle of the upper into 100 the angle between the last and the sole margin.

42. In a machine of the class described, fastening inserting means comprising a fastening guiding nozzle shaped to enter the angle between the last and the projecting 10 sole margin of a stitch-down shoe, means for clamping the marginal portion of the upper of said shoe against the side of the nozzle remote from the last, and means for moving the last over the opposite side of 11 said nozzle while the upper is held by said clamping means.

43. In a machine for progressively lasting stitch-down shoes, a lasting tool having an upper engaging end and presenting to the 11 side of the last a smooth upper wiping face and having formed therein a fastening guide, said guide being arranged to guide a staple substantially to that edge of said end which is formed by the intersection of said 12 face and said end and to maintain said staple substantially parallel to said edge, in combination with sole engaging means, said tool and said engaging means being relatively movable in such a direction that the wiping 12 action of said wiping face will be approxi-

mately parallel to said direction of relative movement, manually operated means for effecting an initial relative movement of said tool and said engaging means of the character specified, and power operated means for completing the said relative movement of said tool and said engaging means.

In testimony whereof I have signed my name to this specification in the presence of two subscribing witnesses.

ADAM H. PRENZEL.

Witnesses:

C. F. STILL,
L. W. RYAN.

It is hereby certified that in Letters Patent No. 1,117,087, granted November 10, 1914, upon the application of Adam H. Prenzel, of Halifax, Pennsylvania, for an improvement in "Machines for Use in Lasting Boots and Shoes," errors appear in the printed specification requiring correction as follows: Page 4, line 16, before the word "attaching" insert the word *sole*; same page, line 60, for the word "latter" read *later*; page 7, line 76, for the word "rotatively" read *relatively*; and that the said Letters Patent should be read with these corrections therein that the same may conform to the record of the case in the Patent Office.

Signed and sealed this 2nd day of February, A. D., 1915.

[SEAL.]

R. F. WHITEHEAD,

Acting Commissioner of Patents.
